(57) **CLAIM**

The ornamental design for a plurality of separable flexible pouches for medication, as shown and described.

DESCRIPTION

FIG. 1 is a front perspective view of the plurality of flexible separable pouches for medication having at least one pill, tablet shown cut in half, at least in one of the plurality of pouches;

FIG. 2 is a back view thereof;

FIG. 3 is a right side view, the left side view being a mirror image thereof;

FIG. 4 is a top view, the bottom view being a mirror image thereof;

FIG. 5 is another perspective view of the second embodiment of the plurality of flexible pouches for medication, wherein the medication being crushed in at least one of the plurality of pouches;

FIG. 7 is a right side view, the left side being a mirror image thereof; and,

FIG. 8 is a top view, the bottom view being a mirror image thereof.

The broken lines showing of portions of the plurality of the medication flexible pouches is included for the purpose of illustrating environmental structure and form no part of the claimed design. The dash-dot-dash lines are perforations, and are part of the claimed design.
